FRENCH FRYER

Victor A. Petertil, Oak Park, Ill., assignor to West Bend Aluminum Co., West Bend, Wis., a corporation of Wisconsin

Application March 26, 1953, Serial No. 24,202

Term of patent 14 years

(Cl. D81—10)

To all whom it may concern:

Be it known that I, Victor A. Petertil, a citizen of the United States, residing in Oak Park, county of Cook, and State of Illinois, have invented a new, original, and ornamental Design for a French Fryer, of which the following is a specification, reference being had to the accompanying drawing, forming a part thereof, and in which:

Fig. 1 is a view in side elevation of a French fryer embodying my new design;

Fig. 2 is a top plan view thereof; and

Fig. 3 is a fragmentary view thereof looking from the right in Fig. 1. The other side not shown is substantially plain.

I claim:

The ornamental design for a French fryer, as shown and described.

VICTOR A. PETERTIL.
